UNITED STATES PATENT OFFICE.

HEBER SCOWCROFT, JR., OF OGDEN, UTAH.

FUEL-FEEDING SYSTEM.

Application filed January 23, 1925. Serial No. 4,209.

To all whom it may concern:

Be it known that I, HEBER SCOWCROFT, Jr., a citizen of the United States of America, and a resident of Ogden, in the county 5 of Weber and State of Utah, have invented certain new and useful Improvements in Fuel-Feeding Systems, of which the following is a specification.

The invention relates to liquid fuel feeding systems adapted especially for use in connection with internal combustion engines and utilizes a reserve fuel or gasoline tank located between the main supply tank and the vacuum feed tank.

10 The invention contemplates the use of a reserve tank as a part of the fuel feeding system, which tank is filled and remains normally filled while the gasoline is being fed through the system from the main supply tank to the vacuum tank. By the use of manually operated means the supply of gasoline in the reserve tank becomes available for feeding to the vacuum tank when the supply in the main tank is exhausted.

20 25 The invention consists in certain novel combinations and arrangements of parts as will hereinafter be more specifically pointed out and claimed.

In the accompanying drawings I have 30 illustrated one complete example of the physical embodiment of my invention wherein the parts are combined and arranged in accordance with one mode for the practical application of the principles of my invention.

35 Figure 1 is a diagrammatic view illustrating a liquid fuel feeding system in which my invention is embodied.

Figure 2 is an enlarged vertical sectional 40 view of the reserve tank showing the feed connections thereto and control means for rendering the tank operative as a part of the fuel feeding system.

In the drawings for convenience of illustration and a ready understanding of the relation of parts I have indicated a standard form of main supply tank 1 for gasoline or other liquid fuel and provided with a feed pipe 2. The feed pipe is connected as an inlet pipe to the reserve supply tank 3 and the reserve tank is connected by its outlet feed pipe 4 to the well known form of vacuum tank 5. The carburetor 6 is connected by pipe 7 to the vacuum tank, and pipe 8 from the vacuum tank is extended to the intake manifold of the internal com-

bustion engine or other device with which the fuel feeding system is to be employed.

As in the vacuum feed type of fuel feeding systems for internal combustion engines, the 60 operation of the pistons in the engine or motor tends to create in the tank 5 a vacuum and also in the reserve tank 3.

The reserve tank is of suitable capacity. 65 and may contain say one gallon of gasoline. The interior of the tank is entirely sealed from the atmosphere and its flanged top is secured as by screws 10 passing through a cork gasket 11 into the interior attaching 70 ring 12 of the tank.

The feed pipe or inlet pipe 2 from the main tank 1 to the reserve tank extends through a sealed opening in the flanged top 9, and the main branch 13 of this pipe opens to the interior of the reserve tank to fill the 75 same with gasoline.

Within the reserve tank is a stand pipe 14 having a closed bottom end slightly elevated above the bottom of the reserve tank, and the top of the standpipe is also closed 80 and sealed as by a cap plate 15 and screws 16 on the top 9. This standpipe is filled with gasoline through the branch pipe 17 of the feed pipe 2 within the reserve tank.

The outlet pipe 4 from the reserve tank 85 extends through the cap plate 15 and terminates near the bottom of the standpipe. It will be apparent that as the reserve tank is filled with gasoline from the pipe 2 the standpipe 14 is also filled and under normal 90 conditions both the reserve tank and standpipe are filled with gasoline which is drawn by suction from the main tank through pipe 2, stand pipe 14 and feed pipe 4 to the 95 vacuum tank 5.

The level of gasoline in the reserve tank and in the standpipe is equalized by means of holes 18 in the upper end of the standpipe.

As long as a supply of gasoline is maintained in the standpipe the liquid is fed therefrom by way of pipe 4 to the vacuum tank. When the main tank and standpipe have been emptied the supply in the reserve tank is made available for use by transferring the contents of the reserve tank to the standpipe for withdrawal therefrom.

It will be understood that the suction created by operation of the engine tends to create a vacuum in the space at the upper end of the reserve tank not occupied by gasoline. 100 By opening the upper part of the reserve tank to the atmosphere air is admitted there-

to for pressure on the contained gasoline to transfer the gasoline from the reserve tank to the standpipe.

For this purpose I utilize an air valve 19 having a casing 20 in the top 9 of the reserve tank, which valve is manually controlled from the dash board or instrument board of an automobile through a wire connection or rod 21 and bell crank lever 22, the latter pivoted at 23 on the valve casing.

The air control valve is connected with a gasoline control valve 24 in the casing 25 located in the bottom of the reserve tank and adapted to admit gasoline through a pipe 26 to the lower end of the stand pipe.

The valve 24 is pivoted in its casing and has a flexible connection or wire 27 to the air valve. A spring 28 is interposed between the lower end of the valve casing 20 and a washer 29 fixed on the wire connection 27 and the spring holds the air valve 19 and gasoline valve 24 closed while the fuel feeding system is operating under normal conditions.

Should the gasoline supply from the main tank become exhausted and the supply from the standpipe be consumed, a partial vacuum is formed in the standpipe. Then by a pull on the wire 21 the automobile operator can open the air valve to admit atmospheric pressure to the reserve tank and open gasoline valve 24. The air pressure and fluid pressure in the reserve tank now force the gasoline from the reserve tank into the standpipe to again furnish a fuel supply to the outlet pipe 4.

The valves 19 and 24 remain open as long as the reserve supply is being used. After again filling the main tank these valves should be closed and the suction from the engine when operated will fill the fuel feeding system as usual. Should the motorist forget to close the valves 19 and 24 after filling the main tank the engine when operated will draw fuel from the reserve tank until the latter is emptied and the supply will again be cut off because of the fact that the air valve is open. This is an indication to the motorist that his valves 19 and 24 are still open and must be closed before fuel can again be drawn from the main supply tank, through the reserve tank, to the vacuum tank. After this warning the valves 19 and 24 should be closed and the engine starter operated with the accelerator closed and the carburetor on full choke until the engine op-

erates. The reserve tank is now in position for the next emergency.

Having thus fully described my invention what I claim as new and desire to secure by Letters Patent is—

1. In a fuel feeding system a reserve tank and a standpipe therein, an inlet feed pipe normally adapted to fill both tank and standpipe simultaneously, an outlet feed pipe communicating with the standpipe, fuel control means for normally closing communication between said tank and standpipe, vent means for normally closing said tank against atmospheric pressure, and means for opening said tank to the atmosphere, said fuel control means and vent means being so constructed that movement of one means produces a corresponding movement of the other means.

2. In a fuel feeding system the combination of a reserve tank having a stand pipe therein, an inlet feed pipe normally adapted to fill both tank and standpipe simultaneously, an outlet pipe communicating with the standpipe, a normally closed gasoline valve controlling communication between the tank and standpipe, a normally closed vent valve in the tank, operative connections between said valves for causing simultaneous movement thereof and means for opening the latter valve.

3. In a fuel feeding system, the combination with a reserve tank and standpipe therein having air passages in its upper portion communicating with the tank, of a gasoline valve closing communication between the tank and standpipe, a valve closing the tank against atmospheric pressure, means for normally holding said valves in closed position, and means for opening the latter valve, said valves being so connected that movement of one valve produces a corresponding movement of the other valve.

4. In a fuel feeding system the combination with a reserve tank and standpipe therein having air passages in its upper portion communicating with the tank, of a normally closed gasoline valve closing communication between the tank and standpipe, a normally closed air valve in the tank, operative connections between said valves and a spring for normally holding said valves in closed position, and manually operated means for opening said valves.

HEBER SCOWCROFT, JR.
